US0D1044828S

(12) **United States Design Patent** (10) **Patent No.:** **US D1,044,828 S**
Chandran et al. (45) **Date of Patent:** **** Oct. 1, 2024**

(54) **DISPLAY SCREEN OR PORTION THEREOF WITH GRAPHICAL USER INTERFACE**

(71) Applicant: **Masimo Corporation**, Irvine, CA (US)

(72) Inventors: **Prashanth Rengaswamy Chandran**, Irvine, CA (US); **Anand Sampath**, Irvine, CA (US); **Keith Ward Indorf**, Riverside, CA (US); **Sebastian T. Frey**, Laguna Niguel, CA (US); **Bilal Muhsin**, San Clemente, CA (US)

(73) Assignee: **Masimo Corporation**, Irvine, CA (US)

(**) Term: **15 Years**

(21) Appl. No.: **29/800,153**

(22) Filed: **Jul. 19, 2021**

Related U.S. Application Data

(62) Division of application No. 29/624,391, filed on Oct. 31, 2017, now Pat. No. Des. 925,597.

(51) **LOC (14) Cl.** **14-04**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken lines showing the display screen or portion thereof form no part of the claimed design. The remaining broken lines showing text and portions of the graphical user interface form no part of the claimed design.
